UNITED STATES PATENT OFFICE.

MAX SPILLMANN, OF RICHLFIELD, NEW JERSEY, ASSIGNOR TO WORTHINGTON PUMP AND MACHINERY CORPORATION, OF NEW YORK, N. Y., A CORPORATION OF VIRGINIA.

CONDENSING APPARATUS.

Application filed August 29, 1925. Serial No. 53,271.

This invention relates to an improved arrangement of steam condenser and engine exhaust connections which is adapted especially for steam turbines, but which is applicable also to engines of other types.

In both axial and radial flow type turbines, there is a tangential movement of the exhaust which causes a nonuniform distribution of steam through the exhaust connections to the condenser, as well as eddies and counter-currents which interfere with the proper flow of the steam to the condenser.

One object of the invention is to provide for the smooth and evenly distributed delivery of exhaust steam from turbines of either the axial or radial flow type.

Another object of the invention is to provide for the uniform distribution of the exhaust steam to the condensing chamber, so as to secure the full condensing action of all the tubes in a surface condenser, or to all parts of the condensing chamber in a jet condenser.

A further object of the invention is to secure the above results, while at the same time the condenser is supported outside the vertical line of the engine supports, so as to avoid the usual expensive constructions required for proper support of the engine with the condenser directly beneath it.

For a full understanding of the invention, a detailed description of constructions embodying the same in preferred forms will now be given in connection with the drawings forming a part of this specification, and the features forming the invention will then be specifically pointed out in the claims.

In the drawings—

Figure 1 is a diagrammatic end elevation of a radial flow turbine and condenser embodying the invention;

Figure 2 is a similar side elevation looking to the left in Fig. 1;

Figure 3 is a somewhat enlarged view similar to Fig. 1, but showing the condenser and connections in section, and

Figure 4 is a view similar to Fig. 3, showing an axial flow turbine arrangement having a volute only on the condenser.

Figures 5 and 6 are detail axial sections showing diagrammatically different forms of turbine volutes.

Referring now especially to Figs. 1-3, A is the turbine, B the condenser, and C the ex-

haust connections between the two. D is the 55 turbine support, and E the condenser support, which may be of any suitable construction. The condenser is shown as having a cylindrical tube bank 10 with central air off-take 11, although the tubes and air off-take 60 may be arranged otherwise, the usual hot-well 12 being provided at the bottom of the condenser. The exhaust connections C include a volute portion 13 enclosing the tube bank 10 and receiving the steam tangentially, so as to distribute steam throughout the periphery of the tube bank, and this volute 65 condenser portion is connected by exhaust pipe 14 to a volute portion 15 surrounding the turbine rotor 16, receiving the exhaust steam 70 therefrom and forming an elbow by which the exhaust steam connection is carried outside the turbine support D to the condenser, so that the latter lies wholly outside the support D and does not interfere with the construction of any form of turbine support. The steam is thus delivered properly from the 75 turbine and to the condenser and uniformly distributed throughout the condenser without eddies and cross currents. In the construction shown, also, both the turbine and condenser may be supported as desired, without the construction being complicated by the necessity of provision for the condenser being 80 in vertical line with the turbine support. 85

In Fig. 4 an axial flow turbine is shown, the condenser volute 13 being the same as shown in Figs. 1-3. With this axial flow turbine, however, the turbine volute is not shown, but a circular exhaust chamber 17 surrounding the rotor 18 is shown, from which the exhaust pipe 19 extends vertically downward, gradually enlarging to the volute 13. In this construction, the exhaust pipe extends within or between the parts of the engine support 90 D, but this involves no substantial complication or increase of cost, as this is only a large pipe, the condenser itself lying outside the vertical line of the turbine support. 95

It will be understood that the constructions 100 illustrated are shown only as preferred embodiments of the invention as applied to radial and axial flow turbines, and that constructions differing widely in form and arrangement of parts may be used within the 105 invention as defined by the claims. The volute or similar expanding passage from the turbine may expand only radially, as shown

in Fig. 3, or both radially and axially or only axially, as desired in accordance with the condenser arrangement or other circumstances under which it is used. For illustration, there is shown in Fig. 5 a turbine exhaust passage or volute 20 expanding radially and axially and receiving the exhaust from the axial flow turbine rotor 18, and in Fig. 6 a turbine exhaust passage or volute 21 expanding only axially. It will be understood, also, that while it is important that the condenser should be carried outside the vertical line of the engine support, so as to avoid interference therewith, and this feature forms a part of the invention, the broader features of the invention relating to conveying the exhaust steam from the engine to the condenser and the distribution of the steam to the latter, may be used with the condenser positioned and supported in any desired manner.

What is claimed is:

1. A steam condenser comprising a condensing chamber, a volute chamber extending about the condensing chamber, and exhaust connections delivering the steam tangentially to the condensing chamber.
2. A steam surface condenser comprising a shell, a tube bank, a volute chamber extending about the tube bank, and exhaust connections delivering the steam tangentially to the tube bank.
3. A steam condenser comprising a condensing chamber, a steam inlet passage tangential to the condensing chamber extending substantially around the chamber and of uniformly decreasing cross-sectional area.
4. A steam surface condenser having a circular tube bank with an air off-take extending into the tube bank, and a steam inlet passage tangential to the tube bank extending

substantially around the tube bank and of uniformly decreasing cross-sectional area.

5. In a condenser, a shell, a tube bank, and a volute steam chamber extending around said tube bank.

6. In a steam condenser, a shell, a tube bank circular in cross section, and a volute steam chamber extending around said tube bank.

7. In a steam condenser, a shell, a tube bank, a volute steam chamber extending around said tube bank, and an air off-take extending into the tube bank at the smaller terminal of the volute.

8. In a steam condenser, a shell, a tube bank, a volute steam chamber extending around said tube bank and an exhaust connection communicating with the larger terminal of said volute whereby exhaust steam passing into the condenser will enter the tube bank tangentially thereof.

9. In a steam condenser, a shell, a tube bank circular in cross section, a volute steam chamber extending around said tube bank and an exhaust connection communicating with the larger end of said volute whereby exhaust steam will enter the tube bank tangentially of its perimeter.

10. In a steam condenser, a shell, a circular tube bank, a hot well, a steam inlet passage tangential to the tube bank extending substantially around the tube bank and of uniformly decreasing cross-sectional area from its steam entrance, said steam inlet passage extending between the tube bank and hot well whereby condensate during its passage to the hot well will travel through the incoming steam.

In testimony whereof, I have hereunto set my hand.

MAX SPILLMANN.
